AIR COMPRESSOR UNIT

Alfred Hallett, Los Angeles, Calif.

Application October 25, 1934, Serial No. 749,879

12 Claims. (Cl. 230—58)

This invention relates to an air compressor unit, and particularly to air compressor units such as are used in automobile, truck and gasoline service stations, garages and other similar places, or in any place where an air compressor unit is desired.

An object of this invention is to provide a novel air compressor unit that will require a minimum amount of floor space when installed for use.

10 An object is to provide a novel air compressor unit that is simple and compact in its construction and arrangement of parts and in its assembly.

Another object is to provide a novel air compressor unit in which all the working parts may be shielded or practically completely enclosed thereby providing a unit, the working parts of which, will not be likely to injure persons in close proximity thereto; and at the same time insuring adequate ventilation and cooling of the 20 working parts, and ease of accessibility thereto.

Another object is to provide a novel air compressor unit that is novel and neat in appearance, and which may be easily maintained in a clean condition, and which is ornamental and 25 will harmonize with the general architecture of present modern service stations.

A still further object is to provide a novel construction in air compressor units having the above characteristics in which the belt from the 30 motor to the air compressor may be easily, quickly and accurately adjusted.

The invention includes the parts, and combinations of parts more particularly hereinafter described in detail and pointed out in the appended claims.

Other objects, advantages and features of invention may appear from the accompanying drawing, the subjoined detail description, and the appended claims.

40 The accompanying drawing illustrates the invention in a form I at present deem preferable.

Figure 1 is a side elevational view of an air compressor unit constructed in accordance with 45 my invention. A portion of the housing is broken away to disclose parts that would otherwise be hidden.

Fig. 2 is a fragmentary view on enlarged scale, partly in side elevation, and partly in section as 50 viewed on irregular line 2—2, Fig. 1. Dotted lines more or less diagrammatically illustrate an air compressor.

Fig. 3 is a transverse sectional view taken on line 3—3, Fig. 2, looking in the direction of the 55 arrows, and showing in plan the platform for

supporting the motor which is shown in dot and dash lines.

Fig. 4 is a fragmentary side elevational view of the motor supporting platform and associated parts, illustrating the adjustable mounting of 5 such platform.

My invention comprises a base member 1, preferably flat and circular in shape, and having vertical uprights or supports 2 fixed at their lower ends to the base 1 in any suitable manner, as by 10 bolts a, and the upper ends of said uprights are connected to one end of an air receiver tank 3 in any suitable manner, preferably by welding the same thereto. The supports 2 are preferably angle-irons and four in number spaced around 15 tank 3 in quadrilateral relation, and the tank 3 is arranged in vertical position, that is, with its ends 4 one above the other.

The base 1 is provided with an upstanding flange 6 that extends around the periphery of 20 the base a short distance inwardly of the outer edge thereof. The flange 6 forms a stop for the lower edge of a jacket or housing 7 which rests on that portion of base 1 between flange 6 and its outer periphery when assembled. The housing 7 entirely encloses the uprights or supports 2 and is preferably divided into two parts 9, 10 that may be hinged together at one side, as at 11, and the free edges or sides provided with any suitable latch or fastening means 12 to maintain 25 the housing in closed position, or the hinge may be eliminated and latch means 12 substituted therefor.

The housing 7 extends above the lower end 4 of tank 3 and is spaced therefrom and terminates a short distance below a downwardly and outwardly curved flange or hood 5 that is fixed to tank 3. This spacing of housing 7 from the 30 tank 3 and flange 5 forms an air outlet space or passageway 8.

At the lower portion or base of housing 7 an aperture b is provided that forms an air inlet to the housing 7, and a screen 13 covers such aperture to prevent foreign substances passing 35 therethrough.

A suitable air compressor 14 is mounted on base 1 and carries a combined flywheel and pulley wheel 15 having spokes 16 that are dished to form 40 fan blades that draw air into the housing or jacket 7 through the screened opening b, adjacent and in alinement with which the flywheel is mounted as shown in Fig. 1.

A suitable and preferably an electric motor 18 45 mounted on a platform or supporting shelf 19 is 50 55

preferably connected by belts 17 to drive the air compressor 14.

The platform 19 is provided at one end with a pair of depending lugs 20 that are pivotally connected to a pair of uprights 2 by any suitable means, as by the bolts and nuts 21. The opposite end of platform 19 is reduced as at c to form a narrowed extension or tongue 22 that extends underneath the drive pulley d of motor 18 and between the loop defined by the belts 17 trained over pulley d. A cross member 23 is fixed to the uprights 2 opposite those to which the platform 19 is pivoted, and an inverted U-shaped straddle bar 24 is connected to cross member 23 in such manner as to receive and straddle the extension 22 which projects therethrough. A set screw 25 threaded through bar 24 engages the upper side of extension 22 and a set screw 25' engages the under side of extension 22. Each of the set screws 25, 25' is provided with lock nuts f to lock screws 25, 25' in adjusted position. By adjustment of the screws 25, 25' the platform 19 may be raised or lowered so as to permit easy placement or replacement and tensioning of the belts 17, and at the same time secure the platform 19 in rigid adjusted position.

A cross member 26 connected to a pair of uprights 2 at one side of motor 18 provides a support for a suitable automatic pressure switch 27 that is connected by a conduit 28 to tank 3 to control operation of motor 18 depending on the pressure in tank 3.

An air line 29 connects the compressor 14 to the tank 3, and a drain pipe 30 for all lines protrudes from the housing 7 at the bottom thereof. An air gauge 31 and safety valve 32 are connected to tank 3, and inspection openings closed by plugs 33 are also provided in tank 3.

From the foregoing it will be seen that I have provided an air compressor unit which is "vertical" in its installation, that is the air receiver tank 3 is mounted on its end and extends vertically above the air compressor and the operating motor 18 is mounted on an adjustable platform between the motor 18 and tank 3, and that all such working parts are entirely enclosed, except for opening b, but which is screen covered thereby making a neat, compact, and sightly apparatus that is safe from persons contacting its working parts when the housing is in position and which will require but a minimum of floor space, that actually required being only slightly greater than the diameter of the air receiver tank 3.

When the air compressor 14 is operated by motor 18 the fan blade spokes 16 will draw cool air through screened opening b and direct such cool air over the compressor 14 after which it will be deflected over motor 18 and thence through the air outlet passageway 8 at the top of housing or jacket 7, and I have found that by such construction and arrangement of parts that they will thus be effectively cooled and permit them to be enclosed in a housing as above set forth.

65 I claim:

1. In an air compressor unit, the combination of an elongate air receiver tank mounted with its longitudinal axis in a substantially vertical plane; a supporting frame for said tank; an air compressor and operating means for said compressor, both mounted below said tank and within the area delineated by said supporting frame; and a housing having an air inlet adjacent its lower end, said housing enclosing said frame, compressor and operating means and being spaced from

from said tank at its upper edge to form an air outlet passage.

2. In an air compressor unit, the combination of an elongate air receiver tank mounted with its longitudinal axis in a substantially vertical plane; a supporting frame for said tank; an air compressor and operating means for said compressor, both mounted below said tank and within the area delineated by said supporting frame; a housing having an air inlet adjacent its lower end, said housing enclosing said frame, compressor and operating means and being spaced from said tank at its upper edge to form an air outlet passage; and a hood secured to said tank and overhanging the upper edge of said housing and being spaced from said housing.

3. In an air compressor unit, an elongate air receiver tank mounted with its longitudinal axis in a substantially vertical plane; a supporting frame for said tank; an air compressor; a supporting platform pivotally connected at one end to said frame; a cross member secured to said frame; a U-shaped straddle bar connected to said cross member and straddling the free end of said platform; means mounted on said platform and being connected to operate said compressor; and means connected to said cross member and said straddle bar to adjust and secure the free end of said platform in fixed adjusted position relative to said compressor.

4. The combination of an air receiver tank; an air compressor; frame means supporting said tank above said compressor; a platform between said tank and said compressor; hinge means connecting one end of said platform to said frame; means adjustably connecting the other end of said platform to said frame to permit vertical shifting of one end of said platform relative to said compressor; compressor operating means mounted on said platform; and linking means connecting said operating means to said compressor and being adjusted relative to said operating means and compressor by adjustment of one end of said platform.

5. In an air compressor unit; an air receiver tank; a frame supporting said tank; an air compressor mounted within said frame and below said tank; a platform between said tank and said compressor and being pivotally connected at one end to said frame; compressor operating means mounted on said platform; looped belt means connecting said compressor and said operating means; the free end of said platform extending between the loop formed by said belt means; and means to adjust the free end of said platform to increase or decrease the tightness of said belt means connection between said compressor and said operating means.

6. In an air compressor unit; an air receiver tank; a frame supporting said tank; an air compressor mounted within said frame and below said tank; a platform between said tank and said compressor and being pivotally connected at one end to said frame; compressor operating means mounted on said platform; looped belt means connecting said compressor and said operating means; the free end of said platform extending between the loop formed by said belt means; means to adjust the free end of said platform to increase or decrease the tightness of said belt means connection between said compressor and said operating means; and a housing enclosing said frame and having an air inlet at its lower end and being spaced from said tank at its upper end to provide an air outlet passage.

7. In an air compressor unit; an air receiver tank; a frame supporting said tank; an air compressor mounted within said frame and below said tank; a platform between said tank and said compressor and being pivotally connected at one end to said frame; compressor operating means mounted on said platform; looped belt means connecting said compressor and said operating means; the free end of said platform extending between the loop formed by said belt means; means to adjust the free end of said platform to increase or decrease the tightness of said belt means connection between said compressor and said operating means; and a housing enclosing said frame and having an air inlet at its bottom and an air outlet at its top.

8. In an air compressor unit; an air receiver tank; a frame supporting said tank; an air compressor mounted within said frame and below said tank; a platform between said tank and said compressor and being pivotally connected at one end to said frame; compressor operating means mounted on said platform; looped belt means connecting said compressor and said operating means; the free end of said platform extending between the loop formed by said belt means; means to adjust the free end of said platform to increase or decrease the tightness of said belt means connection between said compressor and said operating means; a housing enclosing said frame and having an air inlet at its bottom and an air outlet at its top; and means operated by said compressor operating means to cause a circulation of air throughout said housing during operation of said air compressor.

9. In an air compressor unit; an air receiver tank; a frame supporting said tank; an air compressor mounted within said frame and below said tank; a platform between said tank and said compressor and being pivotally connected at one end to said frame; compressor operating means mounted on said platform; looped belt means connecting said compressor and said operating means; the free end of said platform extending between the loop formed by said belt means; means to adjust the free end of said platform to

increase or decrease the tightness of said belt means connection between said compressor and said operating means; a housing enclosing said frame and having an air inlet at its lower end and being spaced from said tank at its upper end to provide an air outlet passage; and a hood secured to said tank and overhanging the upper end of, and being spaced from, said housing. 5

10. In an air compressor unit, the combination of an elongate air receiver tank mounted with its longitudinal axis in a substantially vertical plane; a supporting frame for said tank; an air compressor and operating means for said compressor, both mounted below said tank and within the area delineated by said supporting frame; a housing having an air inlet adjacent its lower end, said housing enclosing said frame, compressor and operating means and being spaced from said tank at its upper edge to form an air outlet passage; and means for maintaining during operation of said compressor, a circulation of air throughout the interior of said housing. 10 15 20

11. In an air compressor unit, the combination of an air receiver tank; a supporting frame for said tank; an air compressor; operating means 25 for said compressor; means adjustably relating said air compressor and operating means; said compressor and operating means both being mounted within the area delineated by said supporting frame; and a housing enclosing said 30 frame, compressor, and operating means and being spaced from said tank at its upper end.

12. In an air compressor unit, the combination of an air receiver; a supporting frame for said tank; an air compressor; operating means for 35 said compressor; means adjustably relating said air compressor and operating means; said compressor and operating means both being mounted within the area delineated by said supporting frame; a housing enclosing said frame, compressor, and operating means and being spaced from said tank at its upper end; and a hood secured to said tank and overhanging the upper end of, and being spaced from, said housing. 40 45

ALFRED HALLETT.
